[57] CLAIM

The ornamental design for a combined strainer and plug for a sink or the like, as shown and described.

DESCRIPTION

FIG. 1 is a perspective view of a combined strainer and plug for a sink or the like showing my new design;

FIG. 2 is a top plan view thereof;

FIG. 3 is a bottom plan view thereof;

FIG. 4 is a side elevational view thereof; and

FIG. 5 is a cross sectional view taken on line 5—5 of FIG. 2.

FIG. 1.

FIG. 2.

FIG. 3.

FIG. 4.

FIG. 5.
